UNITED STATES PATENT OFFICE.

WILLIAM E. HOLDERMAN, OF MARYSVALE, UTAH.

DEVICE FOR TREATING SLIMES.

SPECIFICATION forming part of Letters Patent No. 738,329, dated September 8, 1903.

Application filed November 15, 1902. Serial No. 131,584. (No model.)

To all whom it may concern:

Be it known that I, WILLIAM E. HOLDERMAN, a citizen of the United States, residing at Marysvale, in the county of Piute and State of Utah, have invented certain new and useful Improvements in Devices for Treating Slimes of Mineral-Bearing Quartz; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to leaching or cyaniding tanks for the economical extraction of the precious metals from the tailings and slimes that are produced during the process of pul-
verizing the mineral-bearing quartz or gangue. It provides effective means for separating the valuable from the waste material and in conducting these resultants to separate depositories. It is compact, strong,
cheaply made, and susceptible of duplication to any desired extent. I am aware that there are different tanks and devices in use to accomplish this result; but I am not aware that any one else has ever used my form of tank, by
which I am enabled to save ninety per cent. to ninety-five per cent. of the precious metals contained in the slime. I attain these results by the mechanism illustrated in the accompanying drawings, in which—

Figure 1 is a front elevation of the invention arranged in duplicate series. Fig. 2 is a perspective of a single tank and a portion of another tank thereon. Fig. 3 is an enlarged end elevation of a single tank, partly broken away; and Fig. 4 is a fragmentary plan of a single tank.

Like letters refer to corresponding parts in the several views.

The letter A indicates a liquid-tight tank or case, made of any preferred material and provided with a discharge-pipe a through the bottom. Valves a' are supplied to these pipes.

B B are vertical strips attached to the four sides of the tank, and b b are corresponding strips laid upon the open floor C, which is in-

clined downward from the back to the front of each tank.

A filtering-cloth or other textile e is ar-
ranged in the tank, being preferably sus- 55
pended from the top, where its edges are held beneath the molding c. Its bottom and four
sides rest against the strips B B and b b.
Pipes D D, furnished with stoppers d d, lead
from the bottom of the filter out through the 60
case A.

In operation the slime or gangue is put with
the cyanid solution in the upper filters and
thoroughly mixed therein. If it is desired to
allow a considerable time for the leaching 65
process, as is necessary in some cases, the pipes
a and D are closed. When the solution has
effected its purpose, the valves a' are opened
and the filtered metal-bearing solution is
drawn out and run into the receiver F, the 70
solution having passed through the textile and
the spaces between the strips B and b and
into the space beneath the floor C. The stop-
pers d are now removed from the pipes D, and
the slime flows out from the filter into the filter 75
of the next tank below, where it is washed
and filtered again or leached again with the
cyanid solution and then passed down into
the next lower tank. This process is con-
tinued until the residue is let out into the 80
troughs G and is conveyed away to the dump.
As soon as the upper tank is emptied it is
filled again with new material, so that the op-
eration is kept up continuously. The wash-
ing referred to may be accomplished with wa- 85
ter delivered through a hose at any stage of
the operation, or the spent liquor, impreg-
nated with cyanid, after the precious metal
has been extracted from it may be advan-
tageously used. 90

In a series of these tanks they are arranged
in stair-like succession, so as to transmit from
each tank to the one next below it the re-
siduum therein, where it is further subjected
to the leaching and filtering process, the 95
valuable wash being drained off from each
tank as the operation proceeds into a com-
mon receptacle and the waste conducted to the
dump.

Having described my invention and the 100
manner of using it, what I claim, and desire
to secure, is—

1. In a device for treating slimes having a liquid-tight case a discharge-pipe provided with a valve in its bottom, an inclined floor in said case, spaced bars on said floor and the 5 sides of the case, a filtering fabric covering said bars, and overlapping the upper edge of the tank, a molding to hold the fabric in operative position and pipes provided with stoppers leading from the filter out through said 10 case substantially as described.
2. In a series of leaching and separating tanks of the character described arranged in stair-like coöperative relation, pipes leading from the bottom of each tank a conduit E to

receive the discharge from said pipes, a reservoir into which said conduit discharges, and pipes in each tank provided with stoppers discharging from the filters through the outer case, into the tank next below it, the pipes from the lowest tank discharging into a waste- 20 trough as herein set forth.

In testimony whereof I affix my signature in presence of two witnesses.

WILLIAM E. HOLDERMAN.
